WITNESS:

UNITED STATES PATENT OFFICE.

JAMES W. FALK, OF LITTLE FALLS, MINNESOTA.

TIE AND CLAMP.

Application filed July 31, 1922. Serial No. 578,727.

To all whom it may concern:

Be it known that I, JAMES W. FALK, a citizen of the United States, residing at Little Falls, in the county of Morrison and State of Minnesota, have invented new and useful Improvements in Ties and Clamps, of which the following is a specification.

This invention contemplates certain improvements over my Patent #1,390,108, the invention in the present instance residing in the construction, combination and arrangement of parts as claimed.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:

Figure 1 is a side elevation of the tie constructed in accordance with the invention.

Figure 2 is a longitudinal sectional view through one of the tie sections.

Figure 3 is a transverse sectional view taken on line 3—3 of Figure 1.

Figure 4 is a top plan view.

Figure 5 is an enlarged fragmentary view, partly in section, showing the manner of associating the rail brace with the clamping means.

Figure 6 is a side elevation of the rail brace.

Figure 7 is an edge elevation.

Figure 8 is a transverse sectional view taken on line 8—8 of Figure 6.

Referring to the drawings in detail, 10 and 11 indicate the sections of a concrete tie, these sections being suitably spaced apart, and connected together by reinforcing elements which project from the adjacent ends

45 of the sections as clearly illustrated. Each tie section is reinforced with spaced reinforcing elements, which are arranged longitudinally of the section, and these elements are indicated at 12. As illustrated, each ele-

50 ment has one extremity offset as at 13, and its opposite extremity extending an appreciable distance beyond one end of the section. The projecting ends of the reinforcing elements of the tie section 10 are

55 threaded, while the corresponding extremities of the reinforcing elements of the sec-

tion 11 are offset as at 14, and provided with openings 15 for the reception of the threaded extremities of the reinforcing elements of the section 10. Nuts 16 are associated 60 with these threaded extremities of the latter mentioned reinforcing elements to hold the tie sections positioned relatively for use.

Each tie section is formed with a recess in the upper surface thereof, which extends 65 across the entire width of the section, this recess being indicated at 17, and of a size and shape to receive a wooden block 18, which is arranged to lie flush with the upper surface of the section. The wooden block 70 of course, provides a cushioning means for the rail 19, which reposes upon the block as illustrated in the drawings. Each section of the tie is provided with a reinforcing element 20, wholly embedded in the section, 75 and extended longitudinally thereof, terminating at points beyond the opposed sides of the recess above mentioned. Each of these reinforcing elements 20 is in the nature of a flat bar arranged edgewise, and 80 from the opposed sides of which project extensions 21. Each reinforcing element 20 is further formed to provide opposed upwardly extending portions 22 which rise from the upper edge of said element, and 85 above the upper section of the tie section, these portions 22 being spaced a distance equal to the width of the block 18, and bracing the latter as shown. The opposed part of each portion 22 is provided with a slot 23, 90 which receives a wedge-shaped key 24, these keys being driven toward each other and arranged to overlie the base of the rail, serving to hold the latter positioned upon the block 18. The keys are held in their given 95 positions, through the instrumentality of threaded elements 25, which are threaded in openings in said portions 22 and arranged to engage the keys as shown. Manifestly, the keys can be quickly and easily positioned to hold the rail upon the block 18, and can also be quickly separated from the portions 22, when it is desired to remove the rail from the tie for any purpose whatsoever.

100 For the purpose of bracing the rails at a curve in the track-way, I make use of bracing elements of the construction illustrated in Figures 6, 7 and 8. This bracing element is of a width equal to the width of 110 the portions 22 of the reinforcing element 20 and is positioned between the head of

the rail and one of the projections 22. This bracing element is indicated at 26, and includes a curved portion 27 to accommodate itself to the head of the rail, while the lower portion of the bracing element is bifurcated as at 28 to receive the adjacent end of the key 24, with which it is associated.

While it is believed that from the foregoing description, the nature and advantages of the invention will be readily apparent, I desire to have it understood that I do not limit myself to what is herein shown and described, and that such changes may be resorted to when desired as fall 15 within the scope of what is claimed.

What I claim is:—

1. A railroad tie comprising spaced reinforcing concrete sections, means for detachably connecting said sections together, each 20 section having a recess, a cushioning element positioned in said recess, and upon which the base of the rail reposes, extensions formed on the reinforcing element of each section, said extensions projecting 25 above the section at the opposed sides of the rail, said extensions having slots, wedge-shaped keys slidable in said slots and adapted to overlie the base of the rail, and means for holding said keys immovably associated with said extensions and said rail for the purpose specified.

2. A railroad tie comprising spaced concrete sections, reinforcing elements embedded in each section and arranged edge-wise, means for securing said sections together, each section having a recess, a wooden block arranged in said recess and lying flush with the upper surface of the section, and upon which the rail is adapted 40 to repose, extensions rising from the upper

edge of each reinforcing element and projecting above the said section at the sides of said recess, and each extension having a slot, a wedge-shaped key passed through each slot, and arranged to overlie the base 45 of the rail, and a threaded element passed through said extension to engage said key and hold the latter in position for use.

3. A concrete tie, a reinforcing element embedded therein, said tie having a recess, 50 a cushioning element arranged in said recess and upon which the rail reposes, extensions projecting from said reinforcing element above the tie and at opposite sides of the rail, said extensions having slots, wedge-shaped keys slidable through said slots and arranged to overlie the base of the rail to hold the latter upon the cushioning element, means for holding the keys in their given 55 position, and a bracing element for said rail, said element having a curved portion to accommodate itself to the head of the rail, and the lower end of said element being bifurcated to receive the adjacent end of said key.

4. A concrete tie, a reinforcing element embedded in said tie, said tie having a recess, a cushioning element arranged in said recess, extensions rising from said reinforcing element above said tie, and at the opposite sides of the rail, said extensions having slots, wedge-shaped keys slidable in said slots, and adapted to engage the base 70 of the rail to hold the latter upon the cushioning element, and a threaded fastening 75 element carried by each extension and adapted to engage the adjacent key to hold the latter in its given position.

In testimony whereof I affix my signature.

JAMES W. FALK.
